TION OF DELAWARE

INK RIBBON FEED FOR PRINTING MACHINES

Original application filed July 28, 1928, Serial No. 296,036. Divided and this application filed November 12, 1930. Serial No. 495,040.

This is a division of our application, Serial No. 296,036, filed July 28, 1928, for printing machines.

This invention relates to an ink ribbon feed for printing machines and the like, and is particularly adapted for use in a printing machine wherein a relatively wide ribbon is employed, which has broad extent over a printing form.

10 The salient objects of our invention are to provide a novel ink ribbon feed mechanism for printing machines which will embody a frame carrying the various parts in order that the mechanism may be removed as a unit from the machine with which it is associated; to provide a mechanism embodying spools disposed at opposite ends of the frame on which spools the ribbon may be arranged for winding on and unwinding therefrom; to 15 provide a mechanism wherein movement may be imparted to one of the spools to wind the ribbon thereon as it is unwound from the other of the spools; to provide a mechanism which will be reversible in order that the 20 ribbon may be wound on either of the spools as it is unwound from the other of the spools; and to provide a mechanism of simple construction embodying a minimum number of parts and which will be efficient and positive 25 in operation.

In the selected embodiment of our invention illustrated in the accompanying drawings:

30 Fig. 1 is a longitudinal sectional view taken adjacent one of the side rails of the printing machine, and showing our improved ribbon feed mechanism;

Fig. 2 is a longitudinal sectional view taken 35 at substantially the medial portion of the machine;

Fig. 2a is an enlarged sectional detail view of a portion of the device shown in Fig. 2;

Fig. 3 is a perspective view of the supporting frame;

Fig. 4 is a transverse sectional view through the ribbon feed mechanism; and

Fig. 5 is a transverse section of the bed 50 showing the manner in which the ribbon frame is mounted.

In the drawings, 5 indicates the main frame including longitudinally extending side bars on which a carriage 6, embodying upper and lower parts, is mounted for reciprocal movement on the frame. In the main frame 5 a bed 7 is provided on which a stationary printing form may be mounted and if desired a suitable means may be provided for moving an address form, or other movable printing device, into relationship with the stationary 55 printing form in the manner set forth in the previously referred to application. In the carriage a roller platen 8 is provided which is movable over the printing form in order that an impression may be made on a sheet, such as indicated by 9, fed thereto from the sheet magazine 10. The sheet is forced into printing relationship with the stationary printing form by the platen and an ink ribbon is interposed between the sheet and the 60 printing form. Such an ink ribbon is indicated by 11 in the drawings, and this invention particularly relates to this ink ribbon and the supporting and feeding means therefor.

A skeleton frame 12 is provided which supports a pair of removable spindles 13, and the ink ribbon is stretched across the stationary printing forms and has opposite ends thereof arranged on the spindles for winding on 65 one of the spools as it is unwound from the other. The frame 12 includes side rails 12', one of which, as shown in Fig. 5, rests in a groove provided in the bed 7 while the other of the side rails 12' bears against a shoulder 70 on the opposite side of the bed 7, and in this manner the ribbon frame 12 is supported on the bed 7. Clamping heads 14, 14', having recesses 15, are fixed to pins 16, 16' which are 75 slidably mounted in diagonally opposite corners of the ribbon frame. A spring 17 is arranged between each head 14 and the ribbon frame to normally urge the heads inwardly. The heads 14' have ratchet teeth 18 thereon, and are provided with recesses 19 to receive the ribbon spindles. Projections 20 are arranged in slots 21 in the spindles and are received in notches 22 in the heads 14'. The ribbon is guided on cross bars 23 at the ends of the ribbon frame. A sliding 80

bolt 24 is arranged in a boss 25 in the front end of the main frame, and carries a pin 26 which is adapted to be engaged by a lug 27 on the bottom of the carriage during its forward movement. An arm 28 is pivoted to the rear end of the sliding bolt and extends upwardly therefrom, and a spring 29 is attached to the rear end of the arm to normally hold the arm up so that when the carriage 10 moves the bolt forwardly, the pin 30 on the arm will engage and operate one of the ratchets 18 for rotating the ribbon spool which is acting as a take-up spool. The spring 29 also serves to return the bolt to normal position 15 when the carriage proceeds on its rearward movement. The forward end of the bolt is recessed at 31 to receive a lug or finger 32 to limit the forward and rearward movement of the bolt. During each forward stroke of 20 the carriage, the bolt 24 will cause the ratchet to turn slightly to wind some of the ribbon from one spindle onto the other spindle. When, however, one spindle is nearly wound and the other nearly unwound, the entire 25 frame 12 may be turned end for end on the printing form, and inasmuch as the ratchets are located diagonally opposite, the spools from which the ribbon is being unwound will now be in position to do the winding.

30 A plate 33 is pivoted to the frame at 34, and it carries a clip 35 made of spring metal and having knobs 36, which extend through holes 37 in the mask 38. The cross bars 23 of the ribbon frame are provided with recesses 39 to receive the knobs 36. A mask 38 having printing openings is provided with the holes 37 so that the knobs 36 may project therethrough to hold the mask on the plate 33. In the form shown, this mask allows 40 certain portions of the body form and the address form to be printed and prevents the platen from coming in contact with the ribbon at the end of the printing stroke.

While we have illustrated and described a 45 selected embodiment of our invention it is to be understood that this is capable of variation and modification, and we therefore do not wish to be limited to the precise details set forth but desire to avail ourselves of such 50 changes and modifications as fall within the scope of the following claims.

We claim:

1. A printing machine comprising a frame having a printing form thereon, a carriage 55 movable on said frame, a ribbon frame, a roller mounted on each end of said ribbon frame for supporting an ink ribbon, a ratchet connected to each roller, and means operated by the carriage for rotating one of said 60 ratchets to wind the ribbon, said frame being adapted to be turned end for end and controlled by the same means for rewinding the ribbon.

2. In a printing machine comprising a 65 frame having a printing form thereon, a car-

riage movable on said frame, a ribbon frame, means for supporting the ribbon frame, a roller mounted on each end of said ribbon frame for supporting an ink ribbon, ratchets connected to said rollers at opposite corners 70 of the frame, and means operated by the carriage for rotating one of the ratchets.

3. A printing machine comprising a frame having a printing form thereon, a carriage movable on said frame, a ribbon frame, a 75 roller mounted on each end of said ribbon frame for supporting an ink ribbon, a ratchet connected to each roller, and means operated by the carriage for rotating one of said ratchets to wind the ribbon.

4. In a printing machine including a bed, a ribbon frame, means for removably supporting said ribbon frame on said bed, ribbon receiving rollers at opposite ends of the frame and having a ribbon thereon arranged for 85 winding on one of the rollers as it is unwound from the other roller, ratchets on said rollers, and means for operating one of said ratchets.

5. In a printing machine including a bed, a ribbon frame, means for removably supporting said ribbon frame on said bed, ribbon receiving rollers on opposite ends of the frame and having a ribbon thereon arranged for winding on one of the rollers as it is unwound from the other roller, a ratchet on each of 90 said rollers, said ratchets being disposed at opposite ends of said rollers, means in said printing machine for operating one of said ratchets whereby said frame may be manipulated from said supporting bed and turned 95 to engage the other of the ratchets with the operating means.

6. A printing machine including a bed, a substantially rectangular ribbon frame, means for removably supporting said ribbon 105 frame on said bed, ribbon receiving rollers on opposite ends of the frame and having a ribbon thereon arranged for winding on one of the rollers as it is unwound from the other of the rollers, ratchets on said rollers arranged 110 at diagonally opposite corners of said frame, and means in said machine for operating on one of said ratchets whereby the ribbon may be wound on the roller associated with the ratchet engaged by said operating means. 115

7. A printing machine including a bed, a ribbon frame embodying side rails, means on said bed for removably supporting the side rails of said frame to hold said frame in said machine, ribbon rollers in said frame adapted 120 to have a ribbon arranged thereon for winding on one roller as it is unwound from the other roller, and means for operating one of said rollers to wind the ribbon thereon.
